UNITED STATES PATENT OFFICE.

MONROE GUETT, OF HARTFORD, CONNECTICUT, ASSIGNOR TO THE HART AND HEGEMAN MANUFACTURING COMPANY, OF HARTFORD, CONNECTICUT, A CORPORATION OF CONNECTICUT.

PUSH-BUTTON SWITCH.

SPECIFICATION forming part of Letters Patent No. 690,946, dated January 14, 1902.

Application filed September 23, 1901. Serial No. 76,203. (No model.)

To all whom it may concern:

Be it known that I, MONROE GUETT, a citizen of the United States, residing at Hartford, in the county of Hartford and State of Connecticut, have invented certain new and useful Improvements in Push-Button Switches, of which the following is a specification.

This invention relates to an electric snap-switch that is operated by means of push-buttons for opening and closing the circuit.

The object of the invention is the production of a compact switch of this nature that can be manufactured cheaply, that operates easily, smoothly, and rapidly, and that will be durable and efficient.

This switch may be made either single or double pole for one, two, or more wires, the switch that is illustrated in the accompanying drawings as embodying the invention being a double-pole two-wire switch.

Figure 1 of the drawings is a side view of this switch with a portion of the receptacle cut away to expose the mechanisms. Fig. 2 is a similar view of the opposite side. Fig. 3 is a view, on an enlarged scale, of one side of the supporting, locking, and latch plates. Fig. 4 is a similar view of the other side of these parts. Fig. 5 is a view of a part of the supporting-plate and the latch and latch-plate. Fig. 6 is a view of a part of the locking-plate and the latch, and Fig. 7 is a sectional view on line xx of Fig. 2 looking as indicated by the arrows.

The receptacle 1 for containing the mechanisms may be made of porcelain or any other suitable material. The wire terminals 2, 3, 4, and 5 are provided with ordinary binding-screws and pole-contacts and are secured in the receptacle in any suitable manner. A frame-plate 6 is attached to the receptacle across one end, and secured to and projecting from the frame-plate is the rigid plate 7, that supports the mechanisms. The locking-plate 8 is pivotally mounted upon a spindle 9, that is held by the supporting-plate. Push-buttons 10, which project through the frame-plate, are connected by strips 11 with the locking-plate on opposite sides of the spindle, so that pushing the buttons oscillates the

plate, Figs. 1 and 2. The locking-plate has 50 an opening with a wall 12, that is formed on the arc of a circle, the center of which is coincident with the axis of the plate. At the ends of this curved wall of the opening through the plate are openings 13, that extend radially of the locking-plate. A lug 14 projects from the locking-plate between the ends 15 and 16 of the spring 17, that is coiled about the hub of the locking-plate, Figs. 3 and 4. When the locking-plate is oscillated 55 in one direction, its lug engages an end of the spring and puts the spring under tension, and when the locking-plate is oscillated in the opposite direction the lug engages with the other end of the spring and puts the spring 60 under tension oppositely. The latch-plate 18 is pivotally mounted upon the spindle. This latch-plate has a lug 19, that extends between the ends of the spring outside of the lug on the locking-plate, so that when the 65 spring is made tense by the movement of the locking-plate lug against one end the other end of the spring tends to throw the latch-plate, Figs. 3 and 4. Pivoted to the latch-plate is a latch 20. The latch has a round 70 hub 21, that projects into the opening 22 in the supporting-plate. At the end of this hub is a triangular stud 23, that projects into the opening through the locking-plate adjacent to the curved wall of that opening, Figs. 3 75 and 4. As the center of the hub of the latch—that is, in the opening in the supporting-plate—is but slightly farther out from the axis of the latch-plate than the center of the pivotal connection between the latch and the 80 latch-plate, the latter is locked against being thrown over by the engagement of the hub with the walls of the opening until the hub of the latch can move out radially of the latch-plate along the opening in the supporting- 85 plate, Fig. 5. The hub cannot thus move as long as the latch-stud is confronted by the curved wall of the opening through the locking-plate, Fig. 6. When the locking-plate is moved by pressure upon the outer push-button and its lug places the spring under tension by engaging with one end, the latch-plate and its lug that is engaged by the other 90 95

end of the spring cannot move until after the locking-plate has been moved so far that one of the radial openings in the locking-plate comes opposite the latch-stud. Then the latch-
5 stud, being unobstructed, permits the hub to move outwardly in the opening in the supporting-plate, so that the force of the spring can throw the latch-plate to the opposite side. The curved locking-wall is of such length
10 that the spring is placed under sufficient tension to quickly throw the latch-plate when the radial slot is opposite the latch-stud, so that the latch can swing outwardly and then inwardly to its normal position in the opening
15 in the supporting-plate as the latch-plate is thrown over. The radial slots are so arranged that it is necessary to push in a button and move the locking-plate slightly farther than its normal position before it will re-
20 lease the latch, and when the pressure is removed from the button the spring will move the locking-plate backward until the latch-stud is opposite the end of the curved wall of the opening through the locking-plate, from
25 which position the latch cannot move outwardly until after the locking-plate has been oscillated to the opposite side.

The poles 24 and 25 project from an insulated plate on the spindle near one end and
30 that is connected with the latch-plate, so as to be thrown into and out of engagement with pole-contacts as the latch-plate is oscillated, Fig. 2. The poles 26 and 27 project from an insulated plate on the spindle near the other
35 end, which plate is connected with the latch-plate by the lug that projects from the latch-plate between the ends of the spring, so that these poles are oscillated into and out of engagement with pole-contacts as the latch-
40 plate is oscillated, Fig. 1. Of course either or both of the poles on either side could be omitted, if desired.

There is no complicated mechanism in this switch to wear out, and all the pieces may be
45 stamped to shape and quickly assembled into a compact structure. There is but little friction, so that the movements are easy, and the action is quick, so that the switch is efficient.

I claim as my invention—

50 1. A snap-switch having a supporting-plate, a spring, a locking-plate oscillated by push-buttons for making the spring tense, a latch-plate oscillated by the spring, and an oscillating latch connected with the latch-plate
55 and extending into an opening in the support-

ing-plate and an opening in the locking-plate, substantially as specified.

2. A snap-switch having a supporting-plate, an oscillating locking-plate, push-buttons connected with the locking-plate, an oscillating 60 latch-plate, a spring, and an oscillating latch connected with the latch-plate and extending into an opening in the supporting-plate and an opening in the locking-plate, substantially as specified.

65 3. A snap-switch having a supporting-plate with a radial opening, a spring, a locking-plate oscillated by the push-buttons for making the spring tense, and having a curved slot and radial openings, a latch-plate oscillated by the spring, and an oscillating latch connected with the latch-plate and extending into the openings in the supporting and locking plates, substantially as specified.

70 4. A snap-switch having a supporting-plate with a radial opening, a spring, a locking-plate oscillated by push-buttons for making the spring tense and having a curved slot and radial openings, a latch-plate oscillated by the spring, a latch pivoted to the latch-plate, and having a hub extending into the opening in the supporting-plate and a stud 80 extending into the opening in the locking-plate, substantially as specified.

75 5. A snap-switch having a supporting-plate with a radial opening, a spring, a locking-plate oscillated by push-buttons for making the spring tense and having a curved slot and radial openings and a lug, a latch-plate oscillated by the spring and having a lug, said 90 lugs on the locking-plate and latch-plate extending between the ends of the spring, and a latch pivoted to the latch-plate and having a hub extending into the opening in the supporting-plate and a stud extending into the 95 opening in the locking-plate, substantially as specified.

6. A snap-switch having a supporting-plate, a locking-plate, a latch-plate, a spring, means for moving the locking-plate and making the 100 spring tense, and a latch pivotally connected with the latch-plate and held from movement along the supporting-plate by the locking-plate until the spring is made sufficiently tense, substantially as specified.

MONROE GUETT.
